UNITED STATES PATENT OFFICE

GEORGE H. GILLIGAN, OF PROVIDENCE, RHODE ISLAND, ASSIGNOR TO U. S. RING TRAVELER COMPANY, OF PROVIDENCE, RHODE ISLAND, A CORPORATION OF RHODE ISLAND

SELF-LUBRICATING TRAVELER

Application filed November 21, 1929. Serial No. 408,777.

My invention relates to travelers for use upon the rings of spinning or twisting machines.

The essential objects of my invention are 5 to provide means in the traveler for lubricating the ring upon which the traveler moves; to automatically discharge the lubricant upon the ring; to afford a broad area of distribution of the lubricant; to attain these ends in 10 a simple and inexpensive structure; and to provide a novel and economical method of constructing the traveler.

To the above ends essentially my invention consists in such parts and combinations of 15 parts, and in such steps and in such combinations of steps, as fall within the scope of the appended claims.

In the accompanying drawings which form a part of this specification,

20 Figure 1 is a perspective view of the tubular blank from which my traveler is formed,

Figure 2, a longitudinal central section of the complete traveler,

25 Figures 3 and 4, sections of the same on lines 3—3 and 4—4 respectively of Figure 2, and

30 Figure 5, a front elevation of the complete traveler mounted in running position upon a ring of the T-type, the latter being shown in cross section.

Like reference characters indicate like parts throughout the views.

35 My traveler is formed from a cylindrical metallic blank 8 cut from a length of hollow wire, shown in Figure 1, provided with a cylindrical axial opening 9 extending throughout its length, and with a hole 10 extending from its periphery to the opening 9 midway the length of the blank.

40 This tubular member is by suitable tools bent whereby its intermediate portion is formed into an arched or substantially semi-circular body 13 with a cylindrical bore or chamber 9, and its end portions are formed 45 into inwardly directed, horizontal horns 14

integral with the body and by compression flattened upon their tops and bottoms somewhat, to increase their breadth whereby their bores or passages 16, continuous with the chamber 9, are transversely substantially elliptical in cross section.

45 In Figure 5 is shown my traveler in running position impelled by the thread or yarn 18, extending from the rolls to the bobbin or spool, moving upon the ring 20 of the horizontal type, comprising the usual base 21, web 22, and T flange 23. The tops of the horns 14 are in contact with the lower faces of the flange; and the free extremities of the former are adjacent or in contact with the web 22.

50 A solid fusible lubricant such as grease is manually injected through the hole 10 into the portions 9 and 16 of the axial passage preferably filling the same to or adjacent the free extremities of the horns. The heat generated in the traveler by its frictional contact with the ring and the yarn gradually liquefies the lubricant, which is slowly fed or discharged upon the lower faces of the flange 23 and upon the sides of the web 22, thus preventing both wear of the traveler, and the 55 generation of a warping temperature of the latter.

60 While improved results are attained by the tubular horns of circular or other cross sectional shapes differing from that described, it is found that even superior results are attained when the horns are flattened.

65 It will be observed that the lubricant is automatically fed from the traveler, and that the construction from a tubular blank involves a minimum of effort, time, and expense.

70 I claim:—

75 1. A traveler for spinning or twisting rings comprising a tubular arched body and tubular horns, said body being provided intermediate its length with a hole for the reception of a lubricant.

80 2. A traveler for a spinning or twisting ring comprising an arched body provided 85 with a cylindrical axial opening, a hole for the reception of a lubricant, and a hole 90

with a central longitudinally disposed chamber and with a hole at the apex of the body communicating with the chamber, and horns integral with the body provided with passages continuous with the chamber.

3. A traveler for a spinning or twisting ring comprising a cylindrical arched body provided with a cylindrical chamber, and broad flat horns provided with passages communicating with the chamber.

10 In testimony whereof I have affixed my signature.

GEORGE H. GILLIGAN.
